CONCEALED HINGE

Joseph Soss, Roselle, N. J.

Application April 22, 1938, Serial No. 203,520

6 Claims. (Cl. 16—135)

This invention relates to concealed hinges and particularly to the construction of the housing butt part of hinges of this type, and the object of the invention is to provide a housing butt part 5 formed from a single sheet metal blank folded to form a U-shaped housing portion with attaching plates extending from one side edge of top and bottom walls of the housing at an angle greater than 90° to the web of the housing so as 10 to adapt the housing butt of the hinge to a wide throw hook-shaped butt, and with these and other objects in view the invention consists of a device of the class and for the purpose specified, which is simple in construction, efficient in use, 15 and which is constructed as hereinafter described and claimed.

The invention is fully disclosed in the following specification, of which the accompanying drawing forms a part, in which the separate parts 20 of my improvement are designated by suitable reference characters in each of the views, and in which:

Fig. 1 is a plan view of a hinge made according to my invention with part of the construction broken away and also indicating the open and closed positions of the butts.

Fig. 2 is a view looking in the direction of the arrow 2 of Fig. 1.

Fig. 3 is a side edge view of the hinge as seen 30 in Fig. 1.

Fig. 4 is a view similar to Fig. 1 showing a modification.

Fig. 5 is a section substantially on the line 5—5 of Fig. 4, and

Fig. 6 is a plan view of a blank from which one of the butts of the hinge is formed.

In Figs. 1 to 3 inclusive I have shown a hinge consisting of a hook arm butt part 10 and a housing butt part 11. The hook arm part in the structure shown is substantially in the form of a bolt or rod shaped to form the desired hook-shaped arm 12. One straight end of the rod 13 is threaded to receive nuts or other attaching devices 14, whereas the other end of the arm is enlarged as seen at 15 to form a desired bearing for the pintle 16 of the hinge.

The butt part 11 is formed from a blank 11a shown in Fig. 6 of the drawing. The blank consists of two substantially rectangular plate portions 17 extending into wall portions 18 which form the top and bottom walls of the housing of said butt part which are joined by a web or wall 19. The blank is so shaped and folded as to bring the web or wall 19 of the housing in the angular position with respect to the attaching

plates 17, as seen in Fig. 1 of the drawing, as well as to offset the web 19 with respect to one side of the attaching plates. The angularity between these wall portions is greater than 90° as will be apparent. At this time it will be understood, however, that this angularity may be varied to suit different types and kinds of hinges or installations of hinges.

The wall portions 18 also include protruding pintle bearing portions 20 which are arranged on the inner side of the web 19 when the butt 11 is formed, as will be apparent upon a consideration of Fig. 1 of the drawing. The portions 20 will be apertured as seen at 21 to receive the pintle 16 of the hinge. At the outer side of the attaching plate portions 17 are projecting tongues or flanges 22 which remain in the plane of the plate 17. These flanges will preferably abut as seen at 23 in Fig. 2 of the drawing when the butt part 11 is completely formed.

It is also preferred that the top and bottom walls 18 be reinforced by V-shaped corrugations 24 to give greater rigidity and strength to said walls and to increase the bearing strength thereof.

In Figs. 4 and 5 is shown a modification in which the butt part 11a differs from the butt part 11 simply in doming the projecting pintle bearing portion 20a outwardly in the manner clearly seen in Fig. 5 of the drawing. The pintle pin or rivet 16a is disposed centrally of the domed portions. The parts or elements 17a, 18a, 19a and 24a are the same as the corresponding parts or elements 17, 18, 19 and 24 of the butt 11.

At 25 is shown a hook arm butt part which is substituted for the butt part 10. The butt part 25 is formed from two similar sheet metal blanks in accordance with the teachings of a companion application Serial No. 203,521 filed of equal date herewith, which application has matured into Patent No. 2,163,713 of June 27, 1939. Each blank is shaped to form an attaching plate portion 26, hook arm portions 27, reinforced as seen at 28. The hook arm portions 27 are disposed one directly upon the other and spot-welded or otherwise secured together as indicated at 29. The ends of the hook arms 27 have outwardly pressed dome portions 30 which seat in the dome bearings 20a of the butt 11a, as clearly seen in Fig. 5 of the drawing. It will also appear that the arms 27 fit snugly within the top and bottom walls 18a of the butt housing 11a so as to provide a strong bearing for the butt 25 in the several positions thereof with respect to the butt part 11a.

With both forms of construction shown, the outward swinging movement of the butts 10, 25

is checked by the engagement of the hook arm with the angular web 19, 19a in the manner indicated in dotted lines in Fig. 1 of the drawing. As previously stated, the angularity of this web 5 and its arrangement with respect to the pintle of the hinge may be varied, within certain limits, to suit various types and kinds of installations. In like manner the shape and contour of the hook arm of the butts 10, 25 may be varied. 10 Both forms of hinges disclosed to illustrate certain uses of my invention are of simple and economic construction, and at the same time a strong and durable hinge is provided which may have many uses, but which has a practical use in hingedly mounting a vertical door in connection with the door frame.

In many types of vehicles, such as motor vehicles, airplanes and the like, the trend of streamlining such vehicles renders it desirable and practical to use the concealed hinges. To satisfy this use, it is also desirable to produce an economical hinge in order that the cost thereof will not be prohibitive. 20

It will also be apparent, however, that a hinge 25 of this type is practical in the mounting of the doors of large cabinets, closets and the like, and in fact in connection with doors or closures of any kind or class where it is desirable and practical to use a hinge of the concealed type.

Having fully described my invention, what I 30 claim as new and desire to secure by Letters Patent, is:

1. A concealed hinge of the class described comprising a hook arm butt part and a housing butt part, said housing butt part being formed from a single blank of sheet material fashioned to 35 form a housing part U-shaped in cross sectional form, consisting of top and bottom plates joined at one end by a web, the forward edges of the top and bottom plates having laterally extending 40 attaching plate portions arranged at an angle greater than 90° to the entire web of said housing and at one side of and independent of said web, and the attaching plate portions including 45 projecting members adapted to abut and arranged at one side of and in spaced relation to the housing portion of said butt.

2. A concealed hinge of the class described comprising a hook arm butt part and a housing butt part, said housing butt part being formed from a single blank of sheet material fashioned to 50 form a housing part U-shaped in cross sectional form, consisting of top and bottom plates joined at one end by a web, the forward edges of the top and bottom plates having laterally extending 55 attaching plate portions arranged at an angle greater than 90° to the entire web of said housing and at one side of and independent of said web, the rear edge portions of the top and bottom plates of the housing extending beyond the web to form pintle bearing portions, and the pintle bearing portions being domed outwardly. 60

3. In a concealed hinge of the class described, a housing butt part comprising laterally extending 65 attaching plate portions terminating at adjacent edges in rearwardly extending bearing plates arranged in spaced relation to each other and extending outwardly with respect to one side edge of the attaching plates, said bearing plates being

joined beyond said side edge of the attaching plates and in spaced relation thereto by a web paralleling the angularity of the bearing plates and being arranged in its entirety at an angle greater than 90° to the longitudinal plane of the attaching plates, means at the inner ends of the bearing plates and in spaced relation to said web forming pintle bearings for the pintle of the hinge, and the other side edge of the attaching plates projecting beyond said bearing plates. 10

4. In a concealed hinge of the class described, a housing butt part comprising laterally extending attaching plate portions terminating at adjacent edges in rearwardly extending bearing plates arranged in spaced relation to each other 15 and extending outwardly with respect to one side edge of the attaching plates, said bearing plates being joined beyond said side edge of the attaching plates and in spaced relation thereto by a web paralleling the angularity of the bearing plates and being arranged in its entirety at an angle greater than 90° to the longitudinal plane 20 of the attaching plates, means at the inner ends of the bearing plates and in spaced relation to said web forming pintle bearings for the pintle of the hinge, and said last named means comprising outwardly domed portions on said bearing plates. 25

5. In a concealed hinge of the class described, a housing butt part comprising laterally extending attaching plate portions terminating at adjacent edges in rearwardly extending bearing plates arranged in spaced relation to each other 30 and extending outwardly with respect to one side edge of the attaching plates, said bearing plates being joined beyond said side edge of the attaching plates and in spaced relation thereto by a web paralleling the angularity of the bearing plates and being arranged in its entirety at an angle greater than 90° to the longitudinal plane 35 of the attaching plates, means at the inner ends of the bearing plates and in spaced relation to said web forming pintle bearings for the pintle of the hinge, said last named means comprising outwardly domed portions on said bearing plates, and adjacent portions of the attaching plates and bearing plates being pressed inwardly to form 40 substantially V-shaped stiffening and reinforcing elements. 45

6. In a concealed hinge of the class described, a housing butt part comprising laterally extending attaching plate portions terminating at adjacent edges in rearwardly extending bearing plates arranged in spaced relation to each other and extending angularly and outwardly with respect to one side edge of the attaching plates, 50 said bearing plates being joined beyond said side edge of the attaching plates and in spaced relation thereto by a web paralleling the angularity of the bearing plates and being arranged in its entirety at an angle greater than 90° to the longitudinal plane of the attaching plates, means at the inner ends of the bearing plates and in spaced relation to said web forming pintle bearings for the pintle of the hinge, the other side edge of the attaching plates projecting beyond said bearing plates, and having projecting tongues which abut 55 to reinforce the attaching plates. 60
